UNITED STATES PATENT OFFICE.

DUNCAN CAMERON, OF MINNEDOSA, MANITOBA, CANADA.

VEHICLE-TONGUE.

1,345,125.

Specification of Letters Patent. Patented June 29, 1920.

Application filed May 7, 1918, Serial No. 233,143. Renewed February 13, 1920. Serial No. 358,404.

To all whom it may concern:

Be it known that I, DUNCAN CAMERON, of Minnedosa, in the Province of Manitoba, Canada, have invented certain new and useful Improvements in Vehicle-Tongues, of which the following is a specification.

This invention relates to the construction of the tip of the tongue, and my object is to devise a tongue which can readily be shortened at the tip, which when so shortened will so hold the neckyoke that it will not come off the tongue in the event of the traces being over length or coming unhitched, and which also when shortened will not catch the reins.

I attain my object by means of the constructions hereinafter more specifically described and illustrated in the accompanying drawings in which—

Figure 1 is a side elevation, partly in section, of my improved vehicle tongue showing the tip in its extended position;

Fig. 2 a similar view showing the tip folded back under the tongue;

Fig. 3 a similar view of a modification with the tip in its extended position;

Fig. 4 a similar view of the same showing the tip folded back under the tongue; and

Fig. 5 a plan view of the form shown in Figs. 1 and 2 with the tip extended.

In the drawings like numerals of reference indicate corresponding parts in the different figures.

1 is a vehicle tongue in the main of ordinary type, but cut off somewhat shorter than usual. 2 is the tongue tip, which may be made of any suitable material. I show it in Figs. 1 and 2 as formed of metal, while in Figs. 3 and 4 it is shown as wood strapped with metal to prevent splitting. This tip is hinged by means of the hinge pin 3 to lugs 8 formed on plates secured to the sides of the end of the tongue, so that the tip may be either extended in alinement with the tongue as shown in Fig. 1, or folded back to lie under the tongue as shown in Fig. 2.

When the tip is in the position shown in Fig. 1, the arrangement is substantially the same as in an ordinary tongue, the pole, including the tip, being of substantially the same length as the ordinary one piece tongue. If, however, the traces happen to be a little too long, there is

with this arrangement the possibility that the neck yoke may slip off the tongue. The pole tip is then folded back underneath the tongue as shown in Fig. 2, and the ring 5 of the neckyoke 6 slipped back to engage between the tip and the tongue in such a manner that the neckyoke lies against the end of the tongue. It is impossible for the neckyoke to slip forward off the tongue when the parts are in this position. The same security is given if a trace accidentally becomes unhitched as frequently happens when breaking colts or in the case of a runaway. So also, when the tip is folded back underneath the driving reins cannot catch over the point of the tongue, which is a fruitful cause of accidents and often a source of inconvenience and annoyance to the driver.

It is quite common in the western Provinces in Canada and the western States for teamsters to lead one team with a wagon behind another. Under such conditions a good deal of trouble is caused by the end of the tongue of the led wagon breaking in the end of the box of the leading wagon. With my arrangement the tongue tip may be turned back and this trouble entirely avoided.

To hold the tip extended or folded back as may be desired, I provide the spring 9, which is secured to the under side of the tongue and engages the flat 10 formed on the upper side of the hinge knuckle of the tip when the latter is extended, or the flat 11 on the underside of the hinge knuckle when the tip is folded back. With the construction shown in Figs. 1 and 2, it is preferable to extend the end of the tongue upwardly as shown so as to prevent the possibility of the neckyoke slipping back over the tongue.

In Figs. 3 and 4 I show a modification in which the tip is hinged to the tongue by means of the hinge 13 secured to the under side of the tongue, which hinge is curved down somewhat at its forward end. The tip has a notch 4 formed therein extending from side to side and adapted to receive the ring 5 of the neckyoke 6.

When the weight of the tongue is on the neckyoke, the tip will be held in either position to which it may be adjusted, but to prevent accidental disengagement in case the weight of the tongue is taken off the tip when the latter is folded underneath the

tongue, I provide a spring clip 7 which is connected to the underside of the tongue and adapted to engage part of the tip to releasably hold the latter folded up under the 5 under side of the tongue. With this arrangement the effect is just the same as with that shown in Figs. 1 and 2.

What I claim as my invention is:—

- 10 1. A vehicle tongue having a substantially flat vertical end, a hinge at the end depending below the underside of the tongue, a tip connected to the tongue by said hinge so that it may be swung down out of alinement with the tongue, in combination with a neck yoke adapted to lie against the end of the tongue and a ring connected thereto adapted to embrace the hinge, said tip being shaped to provide a supporting surface which when the tip is 15 swung back on the hinge out of alinement with the tongue will underlie the neckyoke ring.
- 20 2. A vehicle tongue having a tip hinged to fold under the tongue or extend in alinement with the tongue, said tip having a notch formed in its free end for engagement with the ring of a neckyoke.
- 25 3. A vehicle tongue having a substan-

tially flat vertical end, a hinge at the end depending below the underside of the 30 tongue, a tip connected to the tongue by said hinge so that it may be swung down out of alinement with the tongue, in combination with a neck yoke adapted to lie against the end of the tongue and a ring connected 35 thereto adapted to embrace the hinge, said tip being shaped to provide a supporting surface which when the tip is swung back on the hinge out of alinement with the tongue will underlie the neckyoke ring, 40 and a spring for releasably holding the tip in its position out of alinement with the tongue.

4. A vehicle tongue having a tip hinged to fold under the tongue or extend in alinement with the tongue, said tip being shaped to provide a supporting surface which, when the tip is folded back may underlie the ring of the neckyoke used on the tongue.

Signed at town of Mirnedosa Manitoba 50 this 20th day of April 1918.

DUNCAN CAMERON.
